CIRCUIT BREAKER

William A. Forsty, Murrysville, Ronald W. Crookston, Trafford, and August U. Bertolino, Jeannette, Pa., assignors to Westinghouse Electric Corporation

Filed Sept. 10, 1970, Ser. No. 49,921

Term of patent 14 years

Int. Cl. D13—03

U.S. Cl. D26—13

FIG. 1.

FIG. 2.

FIG. 1 is a front perspective view of a circuit breaker embodying our new design; and,

FIG. 2 is a front elevational view of the circuit breaker.

Each of the insulators is the same when viewed from all sides thereof, and the side of the circuit-breaker base, opposite to the one shown in FIG. 1, is a mirror image thereof.

We claim:

The ornamental design for a circuit breaker, substantially as shown and described.
